LINK CHAIN FOR A BRACELET OR SIMILAR
ARTICLE

Michael Chernow, New York, N. Y.

Application November 5, 1949, Serial No. 5,901

Term of patent 14 years

(Cl. D45—16)

To all whom it may concern:

Be it known that I, Michael Chernow, a citizen of the United States and residing at New York, in the county of New York and State of New York, have invented a new, original, and ornamental Design for a Link Chain for a Bracelet or Similar Article, of which the following is a specification, reference being had to the accompanying drawing, forming part thereof, and in which

Fig. 1 is a plan view of the link chain for a bracelet or similar article, showing my new design,

Fig. 2 is a side elevation thereof, and

Fig. 3 is an end elevation of one of the links.

I claim:

The ornamental design for a link chain for a bracelet or similar article, substantially as shown.
MICHAEL CHERNOW.
